BY

UNITED STATES PATENT OFFICE.

JOHN N. SHELLER, OF SOLDIERS HOME, CALIFORNIA.

COMBINED ROCKING AND ROLLING CHAIR.

Application filed August 31, 1922. Serial No. 585,443.

To all whom it may concern:

Be it known that I, JOHN N. SHELLER, a citizen of the United States, residing at Soldiers Home, in the county of Los Angeles and State of California, have invented certain new and useful Improvements in Combined Rocking and Rolling Chairs, of which the following is a specification.

This invention relates to combined rocking and stationary chairs, and a rolling chair, and has for one of its objects to provide a device of this character which may be quickly changed from a rocking or stationary chair to a rolling chair without detaching any of its parts.

Another object of the invention is to provide a device of this character, which may be quickly and easily changed from an ordinary rocking or stationary chair to a rolling chair by the occupant without rising therefrom.

With these and other objects in view the invention consists in certain novel features of construction as hereinafter shown and described and then specifically pointed out in the claims, and in the drawings illustrative of the preferred embodiment of the invention:—

Figure 1 is a side elevation, partly in section, of a part of a conventional rocking chair, with the improvement attached and in elevated or inoperative position.

Fig. 2 is a view similar to Fig. 1, with the improved attachment in depressed or operative position.

Fig. 3 is a transverse section on the line 3—3 of Fig. 1.

The improved device may be applied to chairs of various forms and sizes, but for the purpose of illustration is shown applied to a conventional rocking chair in which 10 represents the seat portion, 11 the legs, 12 the "rounds" or brace members, and 13 the rockers. The rockers are formed with longitudinally directed sockets in their lower faces to receive yieldable bearing members 14, preferably of inflatable tubular construction to form cushioned bearing elements beneath the rockers, to absorb the jars and concussions, as will be obvious. Each of the tubular cushion members will preferably be provided with an air valve indicated at 15, whereby they may be inflated and are secured in any suitable manner to the rockers, for instance by holding bolts indicated at 16.

Attached to the lower face of the seat portion 10 are bearings 17 in which a rock shaft 18 is mounted for oscillation, and depending from the shaft are hangers 19 carrying an axle member 20 upon which carrier wheels 21 are mounted, the latter preferably provided with yieldable tires 22, as shown.

One of the "rounds" 11, for instance the rear "round", is pierced as shown at 23, and mounted to swing at 24 to the axle 20 and passing through the opening 23, is an operating bar 25, the latter preferably curved upwardly at the rear or free end as at 26 and provided with a lifting ring 27.

Formed in the lower face of the bar 25 are spaced notches 28 and 29, to alternately engage the lower side of the opening 23, and thus hold the swinging frame and the bearing wheels in either one of two positions.

The bar 25 is also provided with a leaf spring 30 operative to hold the bar and its attachments yieldably in either one of its two positions.

When the chair is to be used in the ordinary manner, either as a rocker or as a stationary chair, the bar 25 is disposed with its notch 28 in engagement with the bottom of the opening 23, or with the wheels 21—22 above the line of the rockers or the chair frame, as shown in Fig. 1, so that they do not interfere with the ordinary uses of the chair.

If the chair is to be transformed into a rolling chair, the outer curved end 26 of the bar 25 is elevated to release the notch 28 when the frame carrying the wheels will drop by gravity until they engage the floor, indicated at 31. Then the occupant of the chair by simply exerting a slight pushing force rearwardly against the body of the chair will cause the wheels and the swinging frame to serve as a fulcrum to elevate the chair and move the bar 25 forwardly until the notch 29 engages the bottom of the opening 23, as shown in Fig. 2, and "lock" the chair in elevated position and supported entirely by the wheels.

The stationary or rocking chair is thus quickly transformed into a rolling chair by the simple act of the occupant slightly elevating the rear end of the bar 25 and pushing the chair rearwardly to cause the swinging frame and its wheels to assume the position shown in Fig. 2.

The bar 25 with its notches may be arranged to coat with one of the forward rounds instead of one of the rear rounds, but this would not constitute a departure 5 from the principle of the invention.

The improved device is simple in construction, and can be adapted without material structural change to chairs of various forms and sizes.

10 The preferred embodiment of the invention is disclosed in the drawings and set forth in the specification, but it will be understood that modifications within the scope of the claimed invention may be made in the 15 construction without departing from the principle of the invention or sacrificing any of its advantages.

Having thus described the invention, what is claimed as new is:—

20 1. The combination with a rocking chair including a rear transverse brace provided with an opening, of an adjustable rocking frame element depending from the seat portion of the chair and including an axle member 25 provided with a pair of wheels, and an adjustable lever arm pivotally connected to said member and extending rearwardly through said opening and provided with means overlapping the lower wall of said 30 opening for maintaining said element in adjusted position.

2. The combination with a rocking chair including a rear transverse brace provided with an opening, of an adjustable rocking 35 frame element depending from the seat portion of the chair and including an axle member provided with a pair of wheels, an adjustable lever arm pivotally connected to said member and extending rearwardly 40 through said opening and provided with means overlapping the lower wall of said opening for maintaining said element in ad-

justed position, and a resilient element carried by said lever and cooperating with the upper wall of said opening for maintaining 45 the lever in adjusted position.

3. The combination with a rocking chair, of a rock shaft supported from the seat of the chair, angularly adjustable hangers depending from said shaft, an axle member 50 carried by said hangers, wheels mounted on the axle member, and a lever pivotally connected to said member and extending rearwardly from a rear brace of the chair, said lever provided with a means at a plurality 55 of points throughout its length capable of overlapping said brace to maintain said hangers vertically disposed or at an angle causing thereby the shifting of the wheels into and out of contact with the supporting 60 surface of the chair, thereby elevating and lowering the chair.

4. The combination with a rocking chair, of a rock shaft supported from the seat of the chair, angularly adjustable hangers depending from said shaft, an axle member 65 carried by said hangers, wheels mounted on the axle member, a lever pivotally connected to said member and extending rearwardly from a rear brace of the chair, said lever provided with a means at a plurality of 70 points throughout its length capable of overlapping said brace to maintain said hangers vertically disposed or at an angle causing thereby the shifting of the wheels into and 75 out of contact with the supporting surface of the chair, thereby elevating and lowering the chair, and a resilient element carried by said lever and frictionally engaging with the rear brace of the chair and maintaining the lever in its adjusted position.

In testimony whereof, I affix my signature hereto.

JOHN N. SHELLER.
